UNITED STATES PATENT OFFICE.

WILLIAM KRUTZSCH, OF DAYTON, OHIO, ASSIGNOR TO THE BUCKEYE IRON AND BRASS WORKS, OF SAME PLACE.

MEAL-CAKE-MOLDING BOX.

SPECIFICATION forming part of Letters Patent No. 361,879, dated April 26, 1887.

Application filed July 1, 1886. Serial No. 206,846. (No model.)

To all whom it may concern:

Be it known that I, WILLIAM KRUTZSCH, a citizen of the United States, residing at Dayton, in the county of Montgomery and State of Ohio, 5 have invented new and useful Improvements in Meal-Cake-Molding Boxes, of which the following is a specification.

In the manufacture of linseed and other oils the meal from which the oil is to be expressed 10 is inclosed by a sack or piece of textile material and arranged in a molding-box, which is then introduced into a press or former and subjected to a preliminary pressure to form the meal into a compact cake, after which the formed 15 cake is placed in an oil-press to extract the oil from the previously-formed meal-cake. It is a very difficult matter to remove the formed cake after the pressing operation, owing to the fact that the cake adheres or sticks to the sides 20 of the box or cake-former.

To avoid this is the essential object of my invention, which I accomplish by constructing the molding-box in sections laterally adjustable or movable with reference to each other, 25 whereby when the box is removed from the press its sections are or can be separated the one from the other, thereby freeing the sides of the box from the side edges of the formed cake.

30 The invention also has for its object to provide novel means whereby the shape of the cake and the quantity of the meal deposited in the molding-box or cake-former may be varied at will, which I accomplish by providing at 35 each end of the molding-box a removable and replaceable block or plate, as more fully hereinafter described.

The invention is illustrated by the accompanying drawings, in which—

40 Figure 1 is an end elevation of the molding-box or cake-former; Fig. 2, a longitudinal section taken on the line $x x$ of Fig. 1, showing the meal-pan partly drawn out from the molding-box; Fig. 3, a plan view of the molding-box, showing the sections separated and the meal-pan removed; Fig. 4, a transverse sectional view on the line $y y$ of Fig. 6; Fig. 5, a front elevation of Fig. 6; Fig. 6, a plan view of Fig. 5, showing the parts in position for filling 45 the molding-box; Fig. 7, a detail sectional view 50 showing the meeting edges of the sections of the molding-box beveled; Fig. 8, a detail cross-sectional view on the line $z z$ of Fig. 10, showing a modification in the construction of the flaps, hereinafter referred to; Fig. 9, a longitudinal sectional view of one of the modified flaps; Fig. 10, a plan view of Fig. 8; and Figs. 11 and 12, detail views of a modification, hereinafter explained.

55

In order to enable those skilled in the art to 60 make and use my invention, I will now describe the same in detail, referring to the drawings, where the letters $A A'$ indicate the two sections of the molding-box, having attached vertical walls $a a'$. The front section, A , is provided 65 with a suitable handle, D , and is provided at its ends with T -shaped grooves engaging T -headed tongues or guides $L L'$, which are fastened to the wheel-carrying brackets $B B'$ by the T -headed bolts $n n'$.

70

The brackets carry wheels $C C'$, mounted on spindles $b b'$, and the rear section, A' , of the molding-box is rigidly secured to the wheel-brackets, all in such manner that the front section, A , can slide to and from the rear 75 section, A' , to an extent limited by the stops F and e , secured, respectively, to the front section and one of the wheel-brackets. The box-sections are shown separated in Fig. 3, for clearing its sides $a a'$ from the sides of 80 the formed meal-cake. I prefer to bevel the longitudinal meeting edges of the box-sections, as in Fig. 7, so that any meal which may gain access between such meeting edges will fall away and not lodge between them to prevent 85 the perfect closing of the box-sections. To some suitable part of the press, for instance, as in my Letters Patent No. 296,186, dated April 1, 1884, are secured two standards, $h h'$, to which are hinged by arms $g g'$ the end 90 flaps, $G G'$, each of which comprises a hollow metallic casting having an inner beveled or other shaped overhanging edge, r , for the purpose of causing a little less meal to be deposited at the ends of the cake. The edges 95 $l l'$ of the flaps are of such shape that when the flaps are turned down, as in Fig. 6, such edges form a trackway, in connection with the upper edges of the sides $a a'$ of the molding-box, for the travel of the bottomless meal-box to 100 supply the meal to the molding-box, substantially as disclosed in my aforesaid patent.

The two flaps at the rear are rigidly united by a cross-bar, *f*, secured by screws *m n*, while the fronts of the flaps are provided with outwardly-projecting arms *K K'*, to which are secured the ends of the handle-bar *H*, for raising and lowering the two flaps. The fronts of the flaps are also provided with lugs *k k'*, extending toward each other for engaging the ends of the front side, *a*, of the box, Fig. 4, which lugs, in connection with the cross-bar *f*, serve to hold the two sections of the molding-box together while it is being filled with meal. The meal-pan *d*, Fig. 2, is provided with a handle, *e*, by which to manipulate it.

In order to enable the operator to vary at will the shape of the cake and the quantity of meal deposited in the molding-box, I provide the flap-castings *G*, Figs. 8, 9, and 10, with wooden or other plates or blocks *G'*, which are detachably secured to the castings by screws or otherwise. If it is desired to place more or less meal in the molding-box, or to change the shape of the top surface of the cake, one or both of the plates can be removed and planed or fashioned to the required shape and size, after which such plate or plates are replaced in proper position on the casting, or new plates or blocks may be substituted, if desired.

I do not wish to be understood as confining myself to any particular construction of parts for effecting the movement of the molding-box sections with reference to each other to release its sides from the sides of the formed cake, as other constructions than those shown will suggest themselves to those skilled in the art. I may dispense with the wheeled brackets *B B'* and substitute some other contrivance—such, for example, as shown in Figs. 11 and 12, where supporting-bars *B²* are substituted for the wheeled brackets. In this case the rear box-section, *A'*, is rigidly secured to the bars *B²* by screw-bolts *B³*, while the front box-section, *A*, is fitted to slide on said bars by a tongue-and-groove connection, so that it can move to and from the rear section, suitable stops being provided to limit the sliding movement. In operation the molding-box sections are closed together by pushing on the handle *D*, after which the flaps *G G'* are closed down, as shown in full lines, Figs. 4 and 6.

In practice, meal is drawn from a large kettle, called a "heater," into a bottomless box, called a "meal-box." This box sits on a stationary platform, which is of the same shape as the flaps shown in Figs. 8, 9, and 10. This platform is in such a position on the press-frame that when the flaps are swung down they form with it and the sides *a a'* a continuous track, on which the meal-box may slide. When the molding-box *A A'* is drawn out from the press, (which I call a "former,") it strikes against a stop. Its edges *a a'* are then in line with corresponding edges on the stationary platform. The pan *d* is then put in the bottom of the molding-box and a cloth laid upon

it, the two ends of this cloth hanging downward over the ends of the box and pan. The flaps are now swung down, and they bridge the space between the edges *a a'* and the stationary platform. There is now a continuous track, *l l' a a'*, on which the meal-box may slide entirely across the molding-box. When it crosses the latter, it deposits its meal on the aforesaid cloth and strikes off the upper surface to the shape of the top surface of the flaps. It is then shoved back onto the stationary platform, the flaps swung up, and the two ends of the cloth brought up and folded over the top of the meal, the ends of the cloth meeting or overlapping in the center. The molding-box is then shoved into the press (called a "former") and subjected to a moderate pressure. This press is not intended to extract the oil, it being only to form the loose meal into a compact cake. A number of these cakes are put into oil-presses and subjected to a very high pressure. It is this second pressure which extracts the oil. After being subjected to the preliminary pressure, the molding-box is drawn out from the former. The act of drawing it out also frees the cake from the sides of the molding-box, as before explained. The cake is then removed from the molding-box and inserted in the large press. The pan is put back in the molding-box, and the same set of operations repeated indefinitely.

Having thus described my invention, what I claim is—

1. A meal-cake-molding box composed of two sections, one stationary and the other movable laterally in a straight line to and from the stationary section to disengage the walls of the box from the edges of the formed cake, substantially as described.

2. A meal-cake-molding box divided longitudinally into two sections, one of which is movable laterally in a straight line from the other section to separate the sections, and thereby disengage the walls of the box from the edges of the formed cake, substantially as described.

3. A meal-cake-molding box composed of two sections and supports therefor, one section stationary on the supports and the other section having a limited sliding movement on the supports in a straight line to and from the stationary section, substantially as described.

4. A meal-cake-molding box consisting of two sections and supports therefor, one of the sections being stationary on the supports and the other section having a tongue-and-groove connection with the supports, whereby it may be moved to and from the stationary sections, substantially as described.

5. A meal-cake-molding box consisting of a stationary section, a support therefor having a stop, and a laterally-movable section having a stop coacting with the stop on the support for limiting its movement, substantially as described.

6. The combination, in a meal-cake mold-

ing box, of two box-sections and wheeled brackets, on which one section is movable with reference to the other, substantially as described.

5 7. The combination, with a meal-cake-molding box composed of two laterally-separable sections, of a flap, G', provided with a removable and replaceable plate or block, G'', for varying the form of a meal-cake and the quantity of meal supplied to the molding-box, substantially as described.

8. The combination, with a meal-cake-

molding box composed of two laterally-separable sections, of a removable and replaceable plate or block, G'', at one end of the box for varying the form of the meal-cake and the quantity of meal supplied to the molding-box, substantially as described. 15

In testimony whereof I affix my signature in presence of two witnesses.

WILLIAM KRUTZSCH.
